(57) **CLAIM**

The ornamental design for an electric hammer as shown and described.

DESCRIPTION

FIG. 1 is a top, front and left side perspective view of an electric hammer showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1; and,

FIG. 11 is an enlarged view of portion 11 in FIG. 2.

The evenly dashed broken lines in the drawings illustrate portions of the electric hammer which form no part of the claimed design.

The dash-dot-dash broken lines in drawings are provided for annotative purposes to graphically indicate the areas of enlargement. The dash-dot-dash broken lines do not represent actual structure and do not form part of the claimed design.
